CLAIM

The ornamental design for a massage unit for a massage device, as shown and described.

DESCRIPTION

FIG. 1 is a perspective view of a massage unit for a massage device showing my new design;

FIG. 2 is a top plan view thereof;

FIG. 3 is a front elevation view thereof;

FIG. 4 is a rear elevation view thereof; and,

FIG. 5 is a side elevation view thereof, the other side being a mirror image.

The broken lines shown in the figures are for the purpose of illustrating portions of the massage unit for a massage device, which form no part of the claimed design.
